UNITED STATES PATENT OFFICE

STACY B. HASELTINE, OF CHICAGO, ILLINOIS, ASSIGNOR, BY MESNE ASSIGNMENTS,
TO W. H. MINER, INC., A CORPORATION OF DELAWARE

ANTIFRICTION BEARING

Application filed March 17, 1924. Serial No. 699,679.

This invention relates to improvements in antifriction bearings.

One object of this invention is to provide an anti-friction bearing of the roller type especially adapted for use as a railway car side bearing.

More specifically, an object of the invention is to provide effective and efficient means for automatically returning the roller element to normal central position after each actuation thereof without the employment of springs or other relatively fragile devices likely to break or get out of order.

In the drawing forming a part of this specification, Figure 1 is a vertical sectional view taken through portions of body and truck bolsters of a railway car, showing my improvements applied thereto. And Figure 2 is a vertical sectional view taken substantially on the line 2—2 of Figure 1.

In said drawing, 10 denotes the under side of the body bolster and 11 the upper side of the truck bolster of a railway car. As shown, my improved side bearing is applied to the truck bolster and the same consists, broadly, of a retaining member or housing A; an anti-friction element B; and a pair of pendulums or counter weights C.

The housing A is shown as comprising end walls 12 and side walls 13, the latter having elongated, vertically extending openings 14 upwardly from the bottom edge thereof. The housing is also provided with feet or lugs 20 so that the same may be attached to the bolster 11 by rivets or the like. A bearing plate 15, having a hardened wear plate 16 thereon, is secured in place at the bottom of the housing, preferably by peening over portions 40 of the housing member as shown in Figure 1.

The anti-friction element B in the present instance is of the cylindrical roller type, and has axially extending trunnions 17 at its ends. The anti-friction element is adapted to be inserted within the retaining member or housing and to roll back and forth in the bottom thereof, on the wear plate 16.

Counterweights or pendulum members C are arranged one at each end of the anti-friction element, each counter-weight having a main body portion 18 of heavy plate in the

shape of a sector, there being an aperture arranged through the counterweight adjacent the top so as to receive the trunnion 17 rotatably therein, the bottom of the counterweight having a lug or arm 19 extending laterally therefrom substantially centrally between the ends, each lug being adapted to slidably engage in the adjacent, vertically extending slot 14 in the housing. The lower ends of the pendulum members or counterweights are preferably extended below the bottom of the roller and the wear plate 16.

The parts are assembled as follows. The roller B first has the pendulum members C—C applied to the end of the journals 17 and this assembly is then inserted upwardly through the open bottom of the housing or retaining member A. Thereafter, the bearing block 15 with the wear plate 16 thereon is inserted within the space provided therefor in the bottom of the retaining member A, after which the portions 40 are peened over as previously described, from which it will be seen that all of the parts are then held positively in assembled relation as a complete unit and the device may be shipped and applied as such without danger of disarrangement of or tampering with any of the parts.

The normal position of the parts is as shown in full lines. In operation, assuming that the truck bolster remains stationary and the body bolster moves to the left as indicated in dotted lines in Figure 1, the roller will be shifted to the position shown by dotted lines.

As the roller B is shifted, it is evident that there must necessarily be a simultaneous shifting of the pendulums C due to the fact that the latter are carried on the roller journals 17. Inasmuch as the pendulums C have their guide lugs 19 operating in the vertical recesses 14, said pendulums cannot therefore maintain their normal pendant position, but will necessarily be tilted, due to the restriction placed upon their movement by said lugs 19 working in the recesses 14. This will result in the pendulums C assuming the dotted line position shown in Figure 1, where they are obviously in a condition of unstable equilibrium. Upon release of the actuating pressure, it is evident that the

pendulum C would normally tend to swing downwardly about the trunnions 17, but are prevented from having such free action due to the lugs 19 being within the guide recesses 14. This latter engagement, while permitting the centers of mass of the pendulums C to fall, at the same time compels the return of the upper portions of the pendulums to the normal positions shown by full lines in Figure 1, and this in turn obviously insures the return of the roller B.

I have herein shown and described what I now consider the preferred manner of carrying out my invention, but the same is merely illustrative, and I contemplate all changes and modifications that come within the scope of the claims appended hereto.

I claim:

1. In an anti-friction bearing, the combination with a housing open at the top and bottom, said housing being provided with vertical guideways open at the bottom and closed at the top; of a roller within said housing projecting through the top opening thereof, said roller having laterally projecting trunnions; a support within the housing for the roller along which the same is movable, said support being detachable from the housing and closing the bottom opening thereof, said roller being insertible through the open bottom of the housing; and means for holding said roller assembled with the housing and forcentering the roller, including a pair of counter weights, said counter weights having bearing openings receiving the trunnions of the roller and lugs engaging with the guides of the housing, said counter weights being insertible through the open bottom of the housing and the lugs thereof being held against removal from the housing by engagement with the closed ends of the guideways.

2. In an anti-friction bearing for railway cars including body and truck bolsters, the combination with a housing having opposed side walls, said housing being disposed between the body and truck bolsters and mounted on one of said bolsters; of a support within said housing, having an extended bearing surface; a roller movable on said support longitudinally of the bearing surface and cooperating with the opposed bolster, said roller being provided with trunnions at opposite sides thereof; and a pair of counterweights pivotally mounted on said trunnions for swinging movement about the axis of the roller, said counterweights being disposed within the housing and having the weight portions thereof below the axis of rotation of the roller, each of said counterweights having a fixed cylindrical guide projection thereon, below the pivotal center thereof, the side walls of the housing having vertical guideways in which the guide projection of the counterweights are guided for vertical movement while the roller is travel-

ing along said bearing surface, whereby the counterweights are swung to one side when the roller is displaced from centered position to raise the center of gravity of said weights to thereby effect return of the roller to centered position when the load is removed from the same.

In witness that I claim the foregoing I have hereunto subscribed my name this 13th day of March, 1924.

STACY B. HAZELTINE.
